Primary Examiner — Michael C Stout*Assistant Examiner* — Fitzgerald L Butac*(74) Attorney, Agent, or Firm* — Volpe Koenig(57) **CLAIM**

The ornamental design for an engine intake manifold, as shown and described.

DESCRIPTION

FIG. 1 is a perspective view of an engine intake manifold according to our invention;

FIG. 2 is a left side view of our engine intake manifold shown in FIG. 1;

FIG. 3 is a right side view of our engine intake manifold shown in FIG. 1;

FIG. 4 is a front elevation view of our engine intake manifold shown in FIG. 1;

FIG. 5 is a rear elevation view of our engine intake manifold shown in FIG. 1;

FIG. 6 is a top plan view of our engine intake manifold shown in FIG. 1; and,

FIG. 7 is a bottom plan view of our engine intake manifold. The broken lines show portions of an engine intake manifold that form no part of the claimed design.

1 Claim, 7 Drawing Sheets(56)
